UNITED STATES PATENT OFFICE.

WILLIAM J. RAWSON, OF LEWIS RUN, PENNSYLVANIA.

DERRICK.

1,105,455.

Specification of Letters Patent.

Patented July 28, 1914.

Application filed November 26, 1913. Serial No. 803,281.

To all whom it may concern:

Be it known that I, WILLIAM J. RAWSON, a citizen of the United States, residing at Lewis Run, in the county of McKean and State of Pennsylvania, have invented new and useful Improvements in Derricks, of which the following is a specification.

This invention relates to improvements in oil well and like derricks, and particularly to derricks of the knock-down type, commonly constructed of metal piping, the object of the invention being to provide a derrick, the tower of which may be constructed practically completely of piping, and which may be readily and conveniently transported, set up and taken down.

A further object of the invention is to provide a knock-down derrick structure which is simple, cheap and inexpensive, and which possesses maximum strength and durability.

The invention consists of the features of construction, combination and arrangement of parts herein fully described and claimed, reference being had to the accompanying drawings in which:

Figure 1 is a front elevation of a knock-down derrick constructed in accordance with my invention. Fig. 2 is a side elevation of the same. Fig. 3 is a horizontal transverse section through the derrick on line 3—3 of Fig. 1. Fig. 4 is a front elevation on an enlarged scale of a portion of one of the uprights and the cross pieces and braces associated therewith. Fig. 5 is a vertical section on line 5—5 of Fig. 4. Figs. 6 and 7 are horizontal transverse sections on the lines 6—6 and 7—7 of Fig. 4.

Referring to the drawing, 1 designates the base frame of the derrick, which is of the transportable type, and 2 designates the tower of the derrick, which is constructed of piping, and which is preferably of frusto-pyramidal form. The tower 2 comprises a desired number of corner uprights 3 united by front and rear cross pieces 4 and braces 5 and 6, and similar side cross pieces 4' and braces 5' and 6', constructed and arranged as hereinafter fully described. Each upright 3 consists of a plurality of sections 7, 7' detachably coupled together, the proximate ends of adjoining sections being internally threaded, as at 8, to receive a reinforcing and union section 9, which extends equally into the adjacent ends of the sections 7, 7' and both couples and stays said

sections at the joint. The lower end of the union section 9 is fastened into the end of one of the upright sections, as the lower section 7, by a bolt or rivet 10, thus allowing the pipe sections of each upright to be readily and conveniently coupled and uncoupled in setting up and taking down the derrick. The proximate ends of the sections 7 and 7' are provided with collars 11 and 12 which are suitably secured thereto and arranged in abutting relation, and which operate as strengthening and spacing devices. The uprights of the derrick structure are united to each other by sets of front and rear cross pieces 4 and associated braces 5 and 6 and similar side cross pieces 4' and associated braces 5' and 6'. As shown, the cross piece 4 is flattened at each end to form a half-clip 13 which abuts against one of the uprights, while the adjacent end of the upper brace 5 is similarly flattened to provide a co-operating half-clip 14, said clips being united on opposite sides of the upright by bolts 15 and 16, whereby each cross piece 4 and brace 5 are fastened to an upright in a reliable manner, and yet in such a way as to be easily and conveniently attached and detached. The brace 6 is arranged in crossed relation to the brace 5 and is flattened as at 17, at its ends, and perforated for engagement with the bolts 16, whereby all the aforesaid parts are united.

The sets of side cross bars and braces 4', 5' and 6' are arranged in a similar manner to the front and rear cross bars 4 and braces 5 and 6, except that the front and rear sets of cross bars and braces are coupled to the uprights below the joints, while the side sets of cross bars and braces are coupled to the uprights above the joints, thus tying and reinforcing the uprights in a strong and rigid manner. This arrangement also allows the front and rear cross bars to be secured in position upon each lower upright section 7 to serve as supports for a scaffold board or platform on which the workman may stand in setting up the derrick, allowing the next adjacent upper upright section 7 to be applied and the side cross bars to be placed in position, after which the braces may be coupled up, so that the derrick may be erected in a simple, convenient and expeditious manner. Such arrangement also provides for the support of a scaffold board or platform in taking down the derrick section by section, as will be readily understood. The

clamping and fastening members of the parts 4', 5' and 6' are designated by the same primed reference characters, as 13', 14', 15' and 16'.

5 It will be observed from the foregoing description, taken in connection with the drawing, that each upright 3 is connected with the other uprights of the series by sets of cross pieces and stays of the character described, the sets of connections being arranged above and below the abutting collars 11 and 12 whereby the assembled elements are all united at the joint between adjacent sections of the uprights so as to give maximum strength thereto. Sets of connections 15 of the character described unite all the sections of the uprights at the joints, whereby a derrick, which is light in weight, and in which the parts are firmly and strongly 20 united, is provided. Such derrick is superior in strength to derricks of ordinary construction, but at the same time may be readily and conveniently transported, set up for use or knocked down for storage or 25 transportation.

I claim:—

1. A knock down derrick including uprights, each consisting of sections, reinforcing pipes crossing the joints between the 30 abutting ends of adjacent upright sections and secured to one of said sections, collars upon the adjacent ends of upright sections, and sets of connections coupled to each upright above and below the collars of connecting sections and uniting said upright to adjacent uprights, each set of connections comprising a cross piece extending between like joints of adjacent uprights, a bracing upright extending between connected sections 35 of an upright at one level to the connected sections of an adjacent upright at a higher lever, and bolts uniting the adjoining ends of the cross piece and brace and clamping the same to the first-named upright. 40

45 2. A knock down derrick including uprights, and sets of connections between each pair of uprights, each set of connections comprising a cross piece and a bracing member

formed to provide clips disposed on opposite sides of an upright, bolts uniting said clips 50 at opposite sides of the upright, and another bracing member joined to one of said bolts.

3. A knock down derrick including uprights, each consisting of sections, reinforcing pipes crossing the joints between the 55 abutting ends of adjacent upright sections and secured to one of said sections, collars upon the adjacent ends of upright sections, and sets of connections coupled to each upright above and below the collars of connecting 60 sections and uniting said upright to adjacent uprights, each set of connections comprising a cross piece extending between like joints of adjacent uprights, a bracing upright extending between connected sections 65 of an upright at one level to the connected sections of an adjacent upright at a higher level, bolts uniting the adjoining ends of the cross piece and brace and clamping the same to the first-named upright, and a second 70 brace connected with one of said uprights and in like manner clamped with the cross piece to an adjacent upright at the joint of the next lower level.

4. A derrick comprising corner uprights 75 formed of coupled sections, front and rear cross pieces, cross braces coöoperating therewith, said braces being arranged between the cross bars or adjacent tiers of the derrick and one brace of each set being formed with 80 the cross bars to provide clamping members engaging the uprights, bolts connecting the clamping members and to certain of which the other braces are attached, and corresponding side cross pieces and braces, the 85 front cross bars and coöoperating braces being connected with the uprights below the joints and the rear cross bars and coöperating braces being connected with the uprights above the joints. 90

In testimony whereof I affix my signature in presence of two witnesses.

WILLIAM J. RAWSON.
